UNITED STATES PATENT OFFICE.

ROBERT F. BRADBURY, OF WASHINGTON, DISTRICT OF COLUMBIA.

DESIGN FOR A PLATE FOR BUTTON-SHIELDS.

SPECIFICATION forming part of Design No. 30,364, dated March 21, 1899.

Application filed February 15, 1899. Serial No. 705,595. Term of patent 3½ years.

To all whom it may concern:

Be it known that I, ROBERT F. BRADBURY, a citizen of the United States, residing at Washington, in the District of Columbia, have 5 invented and produced a new and original Design for a Plate for Button-Shields, of which the following is a specification.

My new and original design for a plate for a button-shield is shown in the accompanying drawing, which is a perspective view of the plate.

The plate is rectangular in general outline and has its longitudinal edges folded over, as represented at *a*. In the longitudinal axis of

the plate is formed a pear-shaped opening *b*. 15 From the end of the plate toward the larger end of the opening *b* there is a segmental piece cut away or removed, leaving a recess *c*. At the other end of the plate there are short flanges *d*. 20

What I claim is—

The design for a plate for a button-shield, substantially as shown and described.

ROBERT F. BRADBURY.
